UNITED STATES PATENT OFFICE.

PAUL SCHWARZ, OF CROOK, ENGLAND.

GAS-FIRED CONTINUOUS KILN.

1,104,836.

Specification of Letters Patent. Patented July 28, 1914.

Application filed October 23, 1911. Serial No. 656,225.

To all whom it may concern:

Be it known that I, PAUL SCHWARZ, a subject of the King of Great Britain, residing at Crook, in the county of Durham, England, have invented certain new and useful 5 Improvements in Gas-Fired Continuous Kilns, and of which the following is a specification.

This invention relates exclusively to that 10 definite and known type of gas fired kiln, termed the "Hoffmann" kiln, and consists in the combination with a pottery kiln of that type, of certain peculiarly constructed and arranged division walls and gas burners, all 15 as hereinafter particularly described and claimed.

The objects of this invention are to improve the operation of the said Hoffmann kiln; especially to compel the gas and air 20 and the hot products of combustion to thoroughly mix to an even temperature before reaching the goods, to prevent the playing 25 of pointed flames on the goods, to prevent the access to the goods of streaks of cold air, and to obtain an effective 30 down draft, while at the same time retaining the advantages of the horizontal fire travel and the substantially unobstructed continuous floor space which have characterized the Hoffmann kiln as heretofore constructed and operated.

The following description refers to the accompanying drawings, in which,

Figure 1 is a cross section of a kiln of the 35 type mentioned, showing the present invention applied; Fig. 2 is a longitudinal section of a portion of the same kiln, taken at about the line A—B, Fig. 1; and Fig. 3 is a horizontal section of the kiln shown at Fig. 1.

40 Since the present invention consists specifically in a certain combination and arrangement of parts embodied in an improved kiln of the known type termed the Hoffmann, I will first give an outline description of the 45 known Hoffmann kiln with the aid of the accompanying drawings, referring more particularly to Fig. 3, which see. A Hoffmann kiln consists of a structure 1 having an endless tunnel, or burning canal, 2, formed 50 therein, the roof of which is arched transversely of the canal, so as to extend in continuous horizontal lines around the kiln, as viewed in Fig. 2, and through the outer wall 55 of the structure there are passageways or wickets 11 communicating with the said tun-

nel or canal 2, which wickets 11 are formed at suitable distances apart and are closable by doors or other devices. The canal 2 can be divided by one division plate so as to have a beginning and an end, but it never 60 has more than one chamber or compartment. This division plate is indicated at 12, Fig. 3, where it can be inserted through the roof of the tunnel, passing down guideways or 65 grooves; or it may be inserted at any of the positions indicated by the dotted lines 13 in Fig. 3, but only one such plate 12 is employed. Between every two adjacent grooves through which the plate 12 can be slid to divide the canal 2, there communicates at 70 least one flue, such as the flues 8, all of which flues 8 communicate with an internal main flue 7, itself communicating with an uptake, which is indicated sufficiently at 75 Fig. 3 by the dotted lines, and it will be understood that each of the flues 8 is fitted 80 with a damper by which it can be either closed or opened. Usually in this type of kiln which is gas heated, the gas pipes stand up in rows at suitable distances apart from 85 the floor of the canal, and the latter is filled with the goods to be burned, except in one of the spaces between the rows of burners. Thus for example the plate 12 at Fig. 3, as shown, is placed in front of a space marked 90 15, and the burning gases and products of combustion are supposed to be traveling in the direction of the arrows and finding their exit by that flue marked 8*, the damper of which is of course open, while the other flues 8 are closed. The space 15 is supposed 95 to be empty, while the next space 16 contains finished material having little heat, and air is at this time entering by the two wickets 11*, 11*, the doors of which are open. Thus the air entering, comes into contact 100 with material which gradually increases in temperature, the incoming current of air being drawn by natural draft around the entire canal. The space 15 is then filled with the material to be treated, and the compartment 16 is emptied of the finished material; then the plate 12 is moved to the position shown by the dotted line 17; the space 16 is 105 then emptied, and so on. It is also to be understood that in these known kilns the gas burners can be shut off from the gas supply in sections.

In improving this known type of kiln according to my invention, I construct verti- 110

cal division walls 9 and 10 in pairs across the endless canal 2; the division walls being so arranged that they do not stop the flow of the products of combustion around the canal as above described; and each pair of these division walls consists of a transverse front wall 9 and a transverse rear wall 10 at a short distance from said front wall 9. The front wall 9 extends from the top of the canal which extends around the kiln in horizontal lines as aforesaid, but it does not reach the floor; or the said wall is provided with openings 9^x, Figs. 1 and 2, near the base of the canal 2; while the rear wall 10 of each pair does not extend to the roof of the canal and so leaves an opening 10^x, Figs. 1 and 2, between its upper edge and the top of the canal. Between the two walls 9 and 10 of each pair I provide a row of vertical gas burners, 3, in the form of perforated tubes, the gas issuing from the perforations therein, and being supplied by way of subjacent conduits 4, Figs. 1 and 2, from an annular gas canal 5, Fig. 1, in communication with any suitable gas producer 6. By providing a Hoffmann kiln as above described with the said transverse walls 9 and 10, and the arrangement of the gas burners 3 between the said walls, practically the whole canal floor space is rendered available for the reception of goods.

In operating a Hoffmann kiln having the said transverse walls and gas burners arranged and constructed according to this invention as already described, the gas is shut off by the usual valves from the burners 3 at the rear of the plate 12, Fig. 3, and also is shut off from the gas burners between the compartments 15 and 16 as they may now be termed, and it is through these compartments 15 and 16 that the air is admitted by the wickets 11^x, 11^x, while at the other gas burners the gas for consumption is supplied, and the burning products pass around the canal in the direction shown by the arrows, the products of combustion finding their exit by, for example, the flue 8^x.

In the course of its travel, the gaseous heating current will pass beneath the division wall 9 of a pair and over the top of the wall 10 of the same pair, impinging against the ceiling or roof which extends continuously in the direction of said travel in horizontal lines, as shown in Fig. 2, and in passing through the next compartment the gases will descend evenly over the floor area and pass beneath the division wall 9 of the next pair, and so through each compartment the heating products will have a downward direction as indicated by the arrows, for instance at Fig. 2.

By this construction the playing of pointed flames on the goods is avoided, while the arrangement produces an even temperature

goods by reason of the fact that all the air has to first pass through the hot spaces between the cross walls 9, 10.

What I claim as my invention and desire to secure by patent is:—

1. The combination with a gas fired pottery kiln of the Hoffmann type, as hereinbefore specified, comprising a structure containing an endless canal to receive the goods to be treated, the roof of said canal extending continuously in horizontal lines around the kiln, said structure having subjacent gas conduits, a number of passageways through the outer wall communicating with said canal, and flues from said canal communicating with an internal main flue and uptake—of pairs of vertical division walls extending transversely across said canal, each pair of said division walls comprising a front wall and a rear wall at a short distance from said front wall, said front wall extending from said horizontal extending roof of said canal but leaving an opening adjacent to the floor of said canal, and said rear wall extending from the floor of said canal but not reaching the roof thereof so as to leave an opening adjacent to said roof, and a transverse row of upstanding gas burners located within said canal, between the walls comprising each pair of said transverse division walls, and in communication with said subjacent gas conduits.

2. The combination with a gas fired pottery kiln of the Hoffmann type as hereinbefore specified, comprising a structure containing an endless canal to receive the goods to be treated, the roof of said canal being arched transversely of the canal and extending continuously around the kiln; said structure having subjacent gas conduits, a number of passageways through the outer wall communicating with said canal, and flues from said canal communicating with an internal main flue and uptake—of pairs of vertical division walls extending transversely across said canal to divide said canal into compartments each compartment having one of said passageways through said outer wall of said structure and at least one flue communicating with said internal main flue and uptake, each pair of said division walls comprising a front wall and a rear wall at a short distance from said front wall, said front wall extending from the said continuously extending roof of said canal but having through openings adjacent to the floor of said canal, and said rear wall extending from the floor of said canal but not reaching the roof thereof so as to leave an opening adjacent to said roof, and transverse rows of upstanding gas burners in the form of perforated tubes within said canal in communication with said subjacent gas conduits, one of said rows of gas burners being located between the walls compos-

ing each pair of said transverse division walls.

3. A gas fired pottery kiln having, in combination, a main structure containing an endless canal to receive the goods and provided with passageways for goods and air in its outer wall and with gas conduits and escape flues in communication with said canal, the roof of said canal extending continuously in horizontal lines around the kiln and a horizontal floor extending continuously below said roof, transverse rows of upstanding gas burners in the form of vertical perforated pipes within said canal, and 15 pairs of vertical division walls between

which the rows of gas burners are located; the front wall of each pair extending downward from said roof but leaving an opening adjacent to said floor, and the rear wall of each pair extending upward from said floor and leaving an opening adjacent to said roof; substantially as hereinbefore specified, for the purposes set forth. 20

In witness whereof I have hereunto set my hand in the presence of two witnesses.

PAUL SCHWARZ.
